United States Patent [19]

Auerbach et al.

[11] Patent Number: Des. 320,598

[45] Date of Patent: ** Oct. 8, 1991

[54] **PORTABLE KEYBOARD FOR REMOTE CONTROLLER**

[75] Inventors: **Marc Auerbach**, Huntington Beach; **Lawrence D. Emmons**, Grass Valley; **Douglas M. Patton**, Irvine, all of Calif.

[73] Assignee: **Mitsubishi Electric Sales America, Inc.**, Cypress, Calif.

[**] Term: 14 Years

[21] Appl. No.: 430,658

[22] Filed: Nov. 2, 1989

[52] U.S. Cl. D14/115

CLAIM

The ornamental design for a portable keyboard for remote controller, as shown.

DESCRIPTION

FIG. 1 is a top, front, side perspective view of a portable keyboard for remote controller showing our new design;

FIG. 2 is a top plan view thereof;

FIG. 3 is a front elevational view thereof;

FIG. 4 is a rear elevational view thereof;

FIG. 5 is a left-side elevational view thereof;

FIG. 6 is a right-side elevational view thereof; and

FIG. 7 is a bottom plan view thereof.

*Fig. 3**Fig. 2**Fig. 4**Fig. 5*

Fig. 6
